CEMENTING PLUG

Clarence E. Burt, Los Angeles, Calif., assignor to
 Baker Oil Tools, Inc., Vernon, Calif., a corpora-
 tion of California

Application March 16, 1942, Serial No. 434,894

2 Claims. (Cl. 166—1)

The present invention relates to cementing plugs capable of separating charges of cement slurry and other fluids employed in the cementing of casing in well bores.

Cementing plugs must be placed in proper upright position when introduced in a well casing to perform their function of separating charges of cement slurry and mud or other fluids, and thus prevent their commingling and contamination of the slurry. If the plug were inserted in the casing in inverted position, such contamination might occur. In the case of a bottom cement plug employed at the bottom end of a charge of cement slurry, it might be impossible to eject the slurry from the well casing upon engagement of the bottom cementing plug with the internal parts of a well shoe or collar.

Accordingly, it is an object of the present invention to provide an improved cementing plug which cannot be intentionally or inadvertently inserted in a well casing in inverted position.

In its general aspects, the invention contemplates a cementing plug having a packing member adapted to slidably engage the wall of a well casing for the purpose of separating charges of cement slurry and mud. This plug is provided with elements normally extending laterally beyond the periphery of the sealing member in such manner as to prevent introduction of the cementing plug in the casing in inverted position. However, when the plug is in an upright or proper position, these restraining or preventing elements cannot preclude introduction of the plug in the casing, nor its subsequent downward movement with its packing member in slidably sealing engagement with the wall of the casing.

This invention has other objects which will become apparent from a consideration of the device shown in the drawing accompanying and forming part of the present specification. This device will now be described in detail to illustrate the general principles of the invention, but it is to be understood that such detailed description is not to be taken in a limited sense, since the scope of the invention is best defined by the claims appended hereto.

Referring to the drawing:

Figure 1 is a side elevation of a cementing plug embodying the present invention;

Figure 2 is a cross-section taken along the line 2—2 in Figure 1;

Figure 3 is a longitudinal view illustrating an attempt to introduce the plug in a well casing in inverted position; and

Figure 4 is a longitudinal view of the plug in proper position within a well casing.

The specific cementing plug A disclosed in the drawing is designed for operation as a bottom plug. That is, it is placed in the casing B at the lower end of a charge of cement slurry, to prevent contamination between it and the preceding charge of mud or other fluid employed in the well. It is to be understood, however, that the invention is also capable of use in connection with top or other cementing plugs.

The cementing plug includes a body 10 made of any suitable material, such as synthetic resin, rubber, wood, aluminum, magnesium, etc. This body consists of upper and lower portions 11, 12 whose ends 13, 14 are generally cylindrical, and an intermediate portion 15 of reduced diameter. The upper and lower portions of the body taper inwardly toward each other from their cylindrical surfaces to the intermediate portion.

A packing member or disc 16 of rubber or other flexible material is suitably secured to the body at its intermediate portion 15, as by molding, casting or clamping it therein. This packing member is designed to slidably seal with the wall of the well casing B as the plug moves within it, but it is also capable of flexing downwardly upon arresting of the plug body 10 to permit downward by-passing of cement slurry or other fluids around the plug. Such downward flexing of the packing member 16 is allowed by the reduced intermediate portion 15 of the body and the tapered lower surface 12a. Similarly, the packing member may flex upwardly due to the tapered surface 11a of the upper body portion extending from the intermediate portion 15. The generally cylindrical ends 13, 14 of the body serve to prevent substantial tilting of the plug as it moves through the casing.

It is to be noticed that the lower part 12 of the plug body is provided with by-pass openings 17 extending inwardly from its periphery to the plug axis. However, the upper section 11 of the body does not contain such openings. These by-pass openings 17 permit the cement slurry to pass downwardly beyond the flexible packing member 16 and through the openings 17 into and through a casing collar or shoe capable of arresting downward passage of the cementing plug A within the casing.

As the cement slurry is pumped down the casing B with the bottom plug A at its lower end, the flexible packing member 16 probably is deflected slightly in an upward direction and moves 55 downwardly in sealing engagement with the wall

of the casing under the influence of the cement slurry above it and the pumps at the surface of the well bore. Upon striking the internal portion 18 of a cement collar, shoe, or other barrier C in the well casing, the body 10 of the bottom plug can no longer move downwardly, which enables the cement slurry above the plug to deflect the packing member 16 downwardly and inwardly, as permitted by the relieved body portion 12a, and pass into the by-pass openings 17 at the lower end of the plug, from where it may flow through the shoe or collar passage 19 for ejection from the well casing, in a known manner (see Figure 4).

If the bottom cementing plug were to be inserted in the well casing in inverted position, the flat top surface 21 at the normally upper end of the plug body would engage the flat upper end of the internal portion 18 of the shoe or collar and prevent by-passing of the cement slurry around the plug A for passage through the collar C and subsequent ejection from the casing B. The end 21 of the upper plug body portion would make an effective seal with the top of the collar or shoe portion 18 and preclude such passage of cement slurry around the plug. As a result, it would be necessary to pull the entire string of casing from the well bore to eliminate the charge of slurry in the well casing, or, whenever this could not be done, it would become necessary to drill out the cement in the casing and begin the cementing operation over again with the cement plug properly placed in the casing.

In order to avoid the above hazard, it is proposed to incorporate elements in the plug which preclude its insertion in the casing in inverted position, but which do not prevent its proper functioning when inserted in upright position in the casing. In the example shown in the drawing, such elements consist of leaf springs 22 that are molded or otherwise secured to the plug body and have circumferentially spaced fingers 23 extending laterally outwardly and upwardly to a material extent beyond the periphery of the flexible packing member 16. These fingers are disclosed in the drawing as extending outwardly and upwardly from a point adjacent the flexible packing member 16, but it is to be understood that they can be disposed in any other suitable position on the plug body 10.

Should an attempt be made to place the plug in the casing in inverted position, the outwardly extending spring fingers 23 would engage the top 24 of the casing and preclude such introduction (see Figure 3). The resistance to introduction would immediately apprise the operator of the fact that the plug was in the wrong operative position. Upon disposing it in proper upright position, the plug A passes readily into the casing B, since the upwardly extending spring fingers 23 can be deflected inwardly toward the plug body with the exertion of comparatively little force, as permitted by the reduced tapered body portion 11c.

Once the plug is inserted properly in the well 65 casing, the spring fingers 23 merely ride along

the wall of the casing and do not interfere with the ordinary functioning of the plug. As seen in Figure 4, the spring fingers 23 are deflected upwardly and slide along the casing wall without offering much resistance to downward passage of the plug. These spring fingers do not interfere with the slight upward deflection of the packing member 16 as the plug is being moved down through the casing, and also they have no effect whatsoever upon the downward deflection of the packing member upon engagement of the plug body 10 with the shoe or collar C, to permit by-passing of the cement slurry through the bottom plug by-pass openings 17 for ejection from the casing.

It is therefore apparent that a cementing plug has been disclosed which cannot be inserted in a well casing in inverted position, but which can function in its normal intended manner when 20 properly placed in the casing.

I claim:

1. A well cementing plug adapted for use at the bottom end of a charge of cement slurry, including a body having a generally cylindrical imperforate upper portion to prevent flow of liquid therethrough and a lower portion provided with by-pass openings to permit flow of fluid around said plug, said upper and lower portions tapering inwardly toward each other to provide an intermediate portion of reduced diameter, a packing disc secured to said body at said intermediate portion and adapted to slidably seal with the wall of a well casing, and flexible spring fingers secured to said body adjacent and above said packing disc and extending upwardly and radially outward therefrom a material distance beyond the periphery of said packing disc, said flexible spring fingers being deflectable inwardly and away from said packing disc by said casing to permit upright insertion of said plug in said casing, and deflectable outwardly and adjacent said packing disc by the end of said casing if inverted insertion of said plug therewithin is attempted.
2. A well cementing plug adapted for use at the bottom end of a charge of cement slurry, including a body having upper and lower portions, packing means secured to said body for slidable sealing with the wall of a well casing, said upper 40 body portion being imperforate to prevent flow of fluid therethrough and said lower body portion having by-pass openings to permit flow of fluid around said packing means and body, and flexible spring fingers secured to said body adjacent and above said packing means and extending upwardly and radially outwardly therefrom a material distance beyond the periphery of said packing means, said flexible spring fingers being deflectable inwardly and away from said packing means by said casing to permit upright insertion of said plug therewithin and deflectable outwardly and against said packing means by the end of said casing if inverted insertion of said plug therewithin is attempted.

CLARENCE E. BURT.
